UNITED STATES PATENT OFFICE

147,300

DESIGN FOR A WOODWORKING LATHE

Linn Edward Potter, Fayetteville, N. Y.

Application November 16, 1945, Serial No. 123,809

Term of patent 7 years

(Cl. D54—6)

To all whom it may concern:

Be it known that I, Linn Edward Potter, a citizen of the United States, residing at Fayetteville, in the county of Onondaga and State of New York, have invented a new, original, and ornamental Design for a Woodworking Lathe, of which the following is a specification, reference being had to the accompanying drawing, forming part thereof.

Figure 1 is a perspective view of a woodworking lathe embodying my new design;

Figure 2 is a similar view taken from the opposite side of the woodworking lathe.

I claim:

The ornamental design for a woodworking lathe, substantially as shown.

LINN EDWARD POTTER.
